(57) **CLAIM**

The ornamental design for bottle, as shown and described.

DESCRIPTION

FIG. 1 is a perspective view of a bottle showing my new design;

FIG. 2 is a front elevational view thereof, with the rear elevational view being identical;

FIG. 3 is a side elevational view thereof, with the opposite side elevational view being identical; and,

FIG. 4 is a top plan view thereof.

The broken line showing of a pour spout, bottle neck, and bottle base is included for the purpose of illustrating only and forms no part of the claimed design.

1 Claim, 4 Drawing Sheets

FIG. 1

FIG. 2

FIG. 3

FIG. 4
